BASEBALL TRAINING BAT OR SIMILAR ARTICLE

William F. Salisbury, 13924 Premier, Bellflower, Calif.

Filed Mar. 11, 1963, Ser. No. 73,923

Term of patent 14 years

(Cl. D34—5)

FIG. - 1   FIG. - 3   FIG. - 5

FIG. - 2   FIG. - 4

FIG. 1 is a front elevational view of a baseball training bat or similar article, showing my new design;

FIG. 2 is a top plan view thereof;

FIG. 3 is a perspective view wherein the striking head has a flat side and tapers toward the base of the head;

FIG. 4 is a top plan view of FIG. 3; and

FIG. 5 is a front elevational view of FIG. 1 wherein the central portion has a twisted strand appearance.

The characteristic feature of my design resides in a baseball bat having a generally cylindrical head portion joined to a conventional-shaped bat handle portion by a central portion smaller in diameter, all as shown.

I claim:

The ornamental design for a baseball training bat or similar article, substantially as shown and described.
